US0D1091220S

(12) United States Design Patent (10) Patent No.: US D1,091,220 S
(45) Date of Patent: * Sep. 2, 2025

(54) FOOD SMOKER

(71) Applicant: Haijian Ye, Shenzhen (CN)

(72) Inventor: Haijian Ye, Shenzhen (CN)

() Term: 15 Years

(21) Appl. No.: 29/970,089

(22) Filed: Oct. 25, 2024

(30) Foreign Application Priority Data

Jun. 19, 2024 (CN) 202430376920.8

(51) LOC (15) Cl. 07-04

(52) U.S. Cl.

USPC D7/323; D7/368; D7/416; D8/29.1

(58) Field of Classification Search

USPC D7/416, 417, 213, 402, 36, 2, 331, 323;

D8/29.1; D27/141, 154

CPC A23B 4/052; A23B 4/044; C12G 3/06;

C12G 3/07

(57) CLAIM

The ornamental design for a food smoker, as shown and described.

DESCRIPTION

FIG. 1 is a front, right and top perspective view of a food smoker, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the food smoker that form no part of the claimed design.

1 Claim, 8 Drawing Sheets
